UNITED STATES PATENT OFFICE

2,551,017

VENTILATING SILL FOR STORM WINDOWS

Walter M. Krantz, Ferndale, Mich.

Application June 29, 1949, Serial No. 101,979

4 Claims. (Cl. 98—99)

1

This invention relates to storm windows and more particularly to storm windows including double hung sash positioned in a mounting frame and including a vertically adjustable sill.

The principal object of the invention is the provision of a storm sash assembly including a frame having a vertically adjustable sill and means for positioning said sill in said frame.

A further object of the invention is the provision of means for positioning a vertically movable sill in a storm sash frame and providing tension for holding the said sill in predetermined location.

A still further object of the invention is the provision of a storm sash frame incorporating a vertically adjustable sill piece for filling in the area at the bottom of the storm sash frame to compensate for drop sill window constructions.

A still further object of the invention is the provision of a storm sash frame and a vertically movable sill piece and spring tensioned members for holding the said vertically movable sill piece in tight engagement with the frame and/or the sill of the window in which the frame is installed.

The ventilating sill for storm windows shown and described herein comprises a simple and economical means of varying the vertical height of a storm window frame to match a dwelling house window opening in which the same is to be installed. Additionally, the construction disclosed herein provides for controlled ventilation through the window without moving the storm sash in the storm sash assembly. The movable sill portion is held under constant spring tension in the storm window frame by a plurality of spring clips which both mount the ventilating sill on the storm window frame and hold it in any desired position with respect thereto.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is a front plan view of the lower portion of a storm window assembly incorporating a ventilating sill.

Figure 2 is a vertical section on line 2—2 of Figure 1.

2

Figure 3 is a plan view of the inside of the lower portion of the storm window assembly and ventilating sill shown in Figure 1.

Figure 4 is a perspective view of one of the spring clips used in the storm window and ventilating sill assembly shown in Figures 1, 2 and 3.

By referring to the drawings, Figures 1 and 2 in particular, it will be seen that a window casing of a dwelling house window has been partially illustrated and is indicated by the numeral 10. The sill portion thereof is indicated by the numeral 11. A mounting frame 12 is positioned in the opening defined by the casing 10 and the sill 11 and engaged upon the blind stop 13. A storm window frame 14 is secured at its edges in the mounting frame 12 and its lower end is spaced with respect to the sill 11. The frame 14 carries at least one storm sash 15 including a window pane 16.

20 By referring to Figures 2 and 3 of the drawings it will be seen that the frame 14 has a flange 17 with a T headed end section 18 thereon and a rib 19 spaced immediately below the flange 17 and extending inwardly from the depending

25 flange 30. The lowermost edge of the frame 14 is provided with an inturned edge section 20 and a vertically movable sill panel 21, including an inturned transverse flange 22 serving as a handle, is engaged against the inner surface of the frame 14 and the inturned lower edge 20 thereof, as best shown in Figures 2 and 3 of the drawings, so that it forms a closure between the lowermost portion of the storm sash frame 14 and the sill 11.

30 In order that the sill panel 21 may be held in such position, a plurality of spring clips 23 (see Figure 4) are positioned in the frame 14 and between the flange 17 and the rib 19 thereof and in the channel defined by the outer portion of the frame 14 and inner surface of the T head 18 on the flange 17. The spring clips 23 are preferably formed of stainless steel or an equivalent and the main body portion thereof is normally inclined downwardly and forwardly (to the right in Figure 2) and bears against the inner side of the sill panel 21 at a point thereon adjacent the inturned edge 20 of the frame 14.

35 Each spring clip 23 is provided with a right angle section 24 and a pair of oppositely disposed hook-like sections 25, the hook-like sections 25 engaged over the rib 19 and beneath the flange 17 while the right angle section 24 is engaged against an inner surface of the T headed portion 18 on the flange 17. It will thus be 40 seen that any tendency of the sill panel 21 to

move inwardly (to the left in Figure 2) will merely cause the spring clip 23 to more tightly engage itself in position.

It will thus be seen that a simple and efficient means of attaching and tensioning the sill panel 21 is disclosed and which acts in combination with the storm window frame 14 to form an efficient weather-tight closure which may be opened for ventilation, if desired, and which adds a desirable vertical section to the storm window frame enabling the same to compensate for differences in window height as occasioned by drop sill constructions.

In order that the sill panel 21 may be held in desired position, a pair of brackets 26 are positioned on the frame 12 and overlie the outermost edges of the sill panel 21 as best shown in Figures 1 and 2 of the drawings. It will be obvious to those skilled in the art that if desired the brackets 26 may be eliminated and depending sections of the mounting frame 12 utilized in the same manner to secure the sill panel 21 in desired position.

It will thus be seen that the several objects are met by the ventilating sill construction disclosed herein.

Having thus described my invention, what I claim is:

1. The combination of a storm window frame and a ventilating sill panel therefor, said storm window frame including a depending flange whose lower edge is spaced from the sill of the window with which said storm window is used and said ventilating sill panel comprising a member engaged on said depending flange for vertical movement with respect thereto, and a plurality of spring clips engaging said frame and said sill panel and urging the same toward said depending flange, and said sill panel being further characterized by the provision of means on the said depending flange for positioning the said spring clips against movement with respect thereto and whereby the spring clips normally engage and urge the said sill panel against said depending flange.

2. A storm window frame for installation on

drop sill window openings and comprising in combination a rectangular frame and means for increasing the effective height thereof, said means comprising a sill panel slidably engaged against a lower portion of the said frame and a plurality of removable spring clips secured to said frame and engaging the said sill panel on the opposite side thereof with respect to the said frame.

3. The storm window frame and sill panel defined in claim 2 further characterized by the formation and location of the spring clips whereby their lowermost ends terminate adjacent the lowermost portions of the said frame.

4. In a storm window frame having a vertical flange and a pair of spaced extensions on the back thereof, said extensions comprising a T-shaped member connected to said vertical flange by the shank thereof and a rib parallel with said shank and spaced outwardly therefrom and a sill panel movably engaged against the back of the vertical flange, at least one spring clip secured to said frame and engaging and holding the said sill panel against the said vertical flange, the said spring clip comprising a body member having a right angle flange at its uppermost edge and a pair of oppositely disposed hook members formed adjacent thereto and spaced thereby, the said hook members adapted for registry over one of the said extensions on the said vertical flange and the said right angle flange adapted to abut against the other of the said extensions on the said vertical flange of the storm window frame.

WALTER M. KRANTZ.
